HAND OPERATED FIRE EXTINGUISHER OR SIMILAR ARTICLE

Charles K. Huthsing, Jr., Old School Road,
Libertyville, Ill. 60048

Filed Oct. 24, 1969, Ser. No. 19,701

Term of patent 14 years

Int. Cl. D29—01; D23—01

U.S. Cl. D16—2

Fig. 1

Fig. 2

FIG. 3

FIG. 5

FIG. 4

FIG. 1 is a top plan view of a hand-operated fire extinguisher showing my new design;

FIG. 2 is a side-elevational view thereof;

FIG. 3 is a rear-end elevational view thereof;

FIG. 4 is a front end elevational view thereof; and

FIG. 5 is a vertical sectional view therethrough along the line V-V of FIG. 2.

I claim:

The ornamental design for a hand-operated fire extinguisher or similar article, substantially as shown and described.
